UNITED STATES PATENT OFFICE.

EMILIO A. CARDARELLI, OF BOSTON, MASSACHUSETTS.

COMBINATION STEPLADDER.

Application filed December 9, 1925. Serial No. 74,310.

This invention relates to step ladders and more particularly to that type in which the sections are angularly separable in the normal manner and also slidably associated so that they may be used for extension purposes.

A specific embodiment of the invention, together with modifications thereof, will be described with reference to the accompanying drawings, in which,

Fig. 1 is a side elevation of the step ladder in normal position for use;

Fig. 2 is a rear view of the same;

Fig. 3 is a longitudinal section showing the ladder in folded position, with one section extended beyond the other, the middle portion being broken away;

Fig. 4 is a sectional view of the upper portion of the ladder shown in Fig. 2, along line 4—4;

Fig. 5 is an enlarged detail view of the ladder as shown in Fig. 2 with hook locked in closed position;

Fig. 6 is a horizontal section along line 6—6 of Fig. 4; and

Fig. 7 is a side elevation of the ladder shown by Fig. 1, as used in conjunction with a modified form, having a rear section shorter than the front section.

Referring to the drawings, numeral 1 indicates the front section of the ladder and numeral 2 the rear section.

In the front section, the lateral strips 3 are spaced farther apart at the base than at the top and are joined by the series of steps 4, in the usual manner. Strips or guides 5 are fixed to the rear edges of the steps 4 and the strips 3 and carry swivelled hooks 6 having tongues 7, and also loops 8 spaced therefrom a suitable distance and adapted to receive the tongues 7 therein. These strips or guides have parallel inner edges for a purpose later to be described and are tapered from the bottom to the top thereof, whereby their outer edges lie substantially flush with the outer sides of the strips 3.

The second or next to the step 4^a of section 1 is provided with a rearwardly projecting U-shaped retainer or frame 9 (Figs. 4 and 6) having ends 10 and 11 fastened to the step and joined by a cross piece 12 spaced at such distance from the step 4^a as to permit section 2, having parallel sides 13, to be

passed therethrough, when placed against and parallel to the first or front section. 55

The rear section 2 is narrower than the front section and the parallel sides are adapted to fit between the parallel sides of the guides 5 on the front section. The rear section is also provided with a series of steps 14. Adjacent the upper step 14^a is provided a rod 15 passing transversely through the sides 13 and held in position by the engagement of a spring 16 with a slot 17 or the like therein. The rod 15 is adapted to engage the frame or band 9 to prevent complete retraction of the rear section and also serves as a pivot about which the rear section may be opened out into angular position with the first (see Figs. 2 and 4) until the upper end 60 of the rear section engages the cross piece 18 located immediately below the top step 4^b on section 1. To further prevent spreading of the two sections, the tongues 7 of hooks 6 may be inserted into openings or other 65 means for engaging the rear section as at 19.

Upon now disengaging the hooks 6 and folding the two sections 1 and 2 together, they are capable of mutual sliding movement, as shown by Fig. 3, section 2 passing 70 through the band or frame 9 and being held in alignment with the first section by the guides 5 on either side (as indicated by Fig. 2). A bail 21, having a projecting portion 22 and pivoted between the sides 13 at the ends 23, is provided which may be swung over a step 4 of the front section, thereby to support the rear section in raised position, upward movement of the bail being prevented by cross piece 24. As thus adjusted the apparatus may be used as an extension ladder (Fig. 3).

The base of the rear section is provided with laterally extending feet 26, which give the rear section a total width or spread substantially as great as the front section and which contribute added stability when the ladder is in use. By so designing the widths, packing and moving of the ladder is 85 facilitated.

In converting the extension ladder to a step ladder, the rear section is drawn down through the band 9 until the ends of cross rod 15 engage the end portions 10, 11 of the band, thus preventing further downward 90 movement. The lower portion of the rear 100

section is then swung backwardly to the position shown by Fig. 1, when the top of the rear section swings against crosspiece 18. Hooks 8 are then dropped into openings 19 in the step 14 of the rear section. The step ladder, as thus set up, is ready for use in the customary manner, with the additional feature that both front and rear sections are equally useful and may also be used simultaneously, which is not the case with analogous structures which have been heretofore provided.

If now the ladder is to be extended, the hooks 6 are disconnected and the tongues 7 swing into their corresponding loops 8. The rear section is next swung between the guides 5, the sides 13 thereof preventing disengagement of the hooks 6 (Fig. 5). In this position one may slide the rear section 2 upwardly through the band 9 to the desired height and the bail 21 swung over one of the steps 4, thereby supporting it in elevated position.

For this use, the rod 15 may be removed by raising the spring catch 16 from the slot 17 and retracting the same, longitudinally, as will be clear from Fig. 6. When this is done, the rear sections may be withdrawn entirely through the band 9, and the two sections employed independently.

When out of use, the rear section may be raised to disengage the step 4 from the bail 21 which is then swung downwardly, whereupon the rear section may be slid back into juxtaposed position, when the whole occupies a minimum space for storage.

A modification of the device as thus described is shown in Fig. 7, in which the rear section 2^a is of substantially the same general structure but shortened appreciably, thereby adapting the same for use under special conditions, as where unequal levels are encountered, and thus adaptable for pairing up with the usual form of ladder.

as for supporting staging or the like in unusual positions and under varying circumstances.

I claim:

1. A step ladder comprising front and rear sections each provided with steps, a U-shaped retaining frame fixedly secured to the front section near its upper end, said retaining frame embracing the rear section and forming a guide for the latter, a removable stop rod normally extending transversely across the rear section near its upper end, said rod having its ends projecting for engagement with the sides of the U-shaped frame to limit movement of the rear section in one direction, said rod having a recess therein, and a latch member normally engaging said recess to prevent accidental removal of the rod.

2. A step ladder comprising front and rear sections each provided with steps, the front section having guides between which the rear section may be disposed and along which the rear section may slide to form an extension of the front section, pivot means permitting the rear section to swing angularly to the front section, a hook carried by the front section for bracing the rear section when the latter is swung to angular position, and an eye carried by the front section for receiving the hook when the latter is out of use, the eye being spaced from the rear section, when the latter is disposed between the guides of the front section, a distance sufficient to accommodate the body portion of the hook but insufficient to permit withdrawal of the tongue of the hook from the eye so long as the rear section remains between the guides of the front section, thereby preventing accidental disengagement of the hook and eye.

Signed by me at Boston, Massachusetts, this eighth day of December, 1925.

EMILIO A. CARDARELLI.
